(57) **CLAIM**

The ornamental design for a rechargeable battery, as shown and described.

DESCRIPTION

FIG. 1 is a front, top, and right side perspective view of a rechargeable battery showing a first embodiment of our new design;

FIG. 2 is a front, top, and left side perspective view of the first embodiment;

FIG. 3 is a front view of the first embodiment;

FIG. 4 is a rear view of the first embodiment;

FIG. 5 is a top view of the first embodiment;

FIG. 6 is a bottom view of the first embodiment;

FIG. 7 is a right side view of the first embodiment;

FIG. 8 is a left side view of the first embodiment;

FIG. 9 is a front, top, and right side perspective view of a rechargeable battery showing a second embodiment of our new design;

FIG. 10 is a front, top, and left side perspective view of the second embodiment;

FIG. 11 is a front view of the second embodiment;

FIG. 12 is a rear view of the second embodiment;

FIG. 13 is a top view of the second embodiment;

FIG. 14 is a bottom view of the second embodiment;

FIG. 15 is a right side view of the second embodiment; and,

FIG. 16 is a left side view of the second embodiment.

In the drawings, the broken lines defining portions of the rechargeable battery depict environmental subject matter that forms no part of the claimed design. The dash-dot lines represent the boundary between the claimed portions of the rechargeable battery and the unclaimed portions of the rechargeable battery.
